TWO-STAGE PUMP

Allan G. Sheppard, Elmira, N. Y., assignor to
American-La France-Foamite Corporation, Elmira, N. Y., a corporation of New York

Application November 27, 1946, Serial No. 712,632

6 Claims. (CL 103—106)

1

This invention relates to water pumps of the kind appropriate for fire department use and has for its primary object the provision of an improved multi-stage pump of high efficiency and so organized as to be quickly convertible from series to parallel stage operation.

With the foregoing and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings:

Fig. 1 is an elevation of a preferred form of pump according to the invention;

Fig. 2 is a top plan view, partially broken out and sectioned;

Fig. 3 is a section on the line III—III of Fig. 1; Figs. 4 and 5 are sectional views on the lines IV—IV and V—V, respectively, of Fig. 2; and

Fig. 6 is a section on the lines VI—VI of Fig. 2.

In the illustrated embodiment, and as is preferred, the pump includes a main housing 1 of elongated form appropriate for mounting transversely upon a truck chassis with the water inlets 2 and 3 located at opposite ends of the housing so that either one may be conveniently hose-coupled to the water supply source for the pump.

Within the housing, and cast integrally with it, for example, are two casings, generally designated 4 and 5, in which are mounted first and second stage impellers 6 and 7, respectively. The impellers are secured to a common shaft 8 which may be journaled at its ends in the housing side walls 9 and 10.

The casings 4 and 5 are spaced from each other and from the housing side walls so that, with their wall extensions 11, 12, 13, and 14, they constitute partitions extending throughout the major portion of the length of the housing and provide intervening spaces 15, 16 and 17. The latter may conveniently be designated water inlet spaces, all three of them opening at their opposite ends into the end portions of the housing supplied by the water inlets 2 and 3. For convenience, the designations "first" and "second" are sometimes used herein to identify the spaces, passages and so forth, associated with the first and second stage units, respectively.

The first stage unit is of a dual inlet type and, in this instance, though of the same diameter,

2

is of double the capacity of the second stage unit, which is of a single inlet type. As indicated, the first stage unit incorporates dual inlets 18, 19 on opposite sides of the casing 4 and communicating with the first stage inlet spaces 15 and 16, respectively; and the second stage unit incorporates a single inlet 20 communicating with the first stage inlet space 17. As shown particularly in Figs. 4 and 5, the first and second stage casings are provided with discharge passages 21 and 22, respectively, and valve means are provided whereby the two units may be connected, in series or in parallel, to a discharge header 23 to supply a number of hose outlets 24, 25.

To control the coupling of the units to the header there is provided a manually operable valve the construction and operation of which will be apparent from Figs. 2 and 4 of the drawings. In the position illustrated in Fig. 4, the head 26 (constituting the valve proper) occupies its extreme left hand position abutting a seat 27 and the discharge from the first stage unit flows through passage 21 into header 23 as indicated by the full-line arrow. The second stage unit likewise (and at all times) will be discharging directly into the header by way of passage 22. In other words, the units are coupled in parallel.

To convert to series operation the valve 26 is withdrawn by handwheel 28 to its extreme right hand position abutting a seat 29, thereby shutting off the first stage discharge passage 21 from direct communication with header 23. The valve 26 is shown so positioned in Fig. 2. As the valve is thus withdrawn from seat 27 it opens a port 30 and provides an outlet from discharge passage 21 into a passage 31, as indicated by the broken-line arrow in Fig. 4. As appears in Figs. 2 and 3 the passage 31 discharges into the second stage inlet space 17.

To complete the conversion to series operation, means are provided for closing off the second stage inlet space from the housing, so that the second stage supply is derived solely from the first stage discharge (by way of passage 31, as above described). Such means is preferably automatic in the sense of requiring nothing more of the operator than the manipulation of hand wheel 28, and, as shown, may comprise a pair of flow-controlled, hinged valves 32, 33. As will be understood, these valves will be moved to and held in their open position during parallel operation of the units, as a result of the inflow of water from the housing and through inlet space

11 to the second stage inlet 20; whereas when the units are coupled in series in the manner described, the valves will be moved to and held in their closed position by the greater flow (representing the discharge from the larger capacity first stage unit) which enters space 17 from passage 31.

In addition to the structural advantages inherent in the described form and the hydraulic balance effected by the described arrangement of the impellers, the invention lends itself to more efficient operation than can be achieved by any of the customary two stage or four stage pump arrangements. For instance, the impellers may be designed so that when pumping in parallel, approximately 70% of capacity is taken through the double suction first stage and the 30% balance through the single suction second stage. These two stages, representing substantially the practical equivalent of three impellers but without their complexity and space requirements, can satisfy lift conditions not possible with a conventional two stage pump, can provide ample suction to deliver, say 1500 gallons per minute at 150 p. s. i.; and, when converted to series operation, the double inlet first stage impeller has ample suction capacity to ensure net deliveries of 70% of capacity, or 1050 gallons per minute, at 200 p. s. i., and 50%, or 750 gallons per minute at 250 p. s. i. These capacities are available for delivery on a ten foot lift using two lengths of standard six inch suction hose to supply the pump.

In the light of the foregoing description the following is claimed:

1. A two-stage, series-parallel pump comprising: an elongated housing having a water supply inlet at each end; first and second stage impeller casings mounted within the housing and laterally spaced from each other and from the housing side walls to provide first stage inlet spaces between the first stage casing and its proximate housing side wall and between the casings, and a second stage inlet space between the second stage casing and its proximate housing side wall, said three inlet spaces all opening at their opposite ends into the end portions of the housing; a large capacity first stage impeller and a smaller capacity second stage impeller mounted in the respective casings and secured to a common shaft journalled in the said housing side walls; dual casing inlets to the opposite sides of the first stage impeller communicating with said first stage inlet spaces, and a single casing inlet to the second stage impeller communicating with said second stage inlet space; a discharge header; a first discharge passage from the first stage casing communicating with the header and with the second stage inlet space, and a second discharge passage from the second stage casing to the header; a manually operable valve movable to one position to direct the water flow in the first discharge passage to the header only and to another position to direct such flow to the second stage inlet space only; and valve means responsive to movement of the said manually operable valve to its said positions, respectively, to open and to close off communication between the said end portions of the housing and the second stage inlet space.

2. A two-stage, series-parallel pump comprising: a housing; first and second stage impeller casings mounted within the housing and laterally spaced from each other and from the housing side walls to provide first stage inlet spaces between

the first stage casing and its proximate housing side wall and between the casings, and a second stage inlet space between the second stage casing and its proximate housing side wall, said three inlet spaces all opening into a portion of the housing; a water supply inlet to said portion of the housing; a large capacity first stage impeller and a smaller capacity second stage impeller mounted in the respective casings and secured to a common shaft journalled in the said housing side walls; dual casing inlets to the opposite sides of the first stage impeller communicating with said first stage inlet spaces, and a single casing inlet to the second stage impeller communicating with said second stage inlet space; a discharge header; a first discharge passage from the first stage casing communicating with the header and with the second stage inlet space; and a second discharge passage from the second stage casing to the header; a manually operable valve movable to one position to direct the water flow in the first discharge passage to the header only and to another position to direct such flow to the second stage inlet space only; and valve means responsive to movement of the said manually operable valve to its said positions, respectively, to open and to close off communication between the said portion of the housing and the second stage inlet space.

3. A two-stage, series-parallel pump comprising: a housing; first and second stage impeller casings mounted within the housing and laterally spaced from each other and from the housing side walls to provide first stage inlet spaces between the first stage casing and its proximate housing side wall and between the casings, and a second stage inlet space between the second stage casing and its proximate housing side wall; a water supply inlet to a portion of the housing normally in communication with all three of said inlet spaces; a large capacity first stage impeller and a smaller capacity second stage impeller mounted in the respective casings and secured to a common shaft; dual casing inlets to the opposite sides of the first stage impeller communicating with said first stage inlet spaces, and a single casing inlet to the second stage impeller communicating with said second stage inlet space; a discharge header; a first discharge passage from the first stage casing communicating with the header and with the second stage inlet space, and a second discharge passage from the second stage casing to the header; a manually operable valve movable to one position to direct the water flow in the first discharge passage to the header only and to another position to direct such flow to the second stage inlet space only; and valve means movable to open and to close off communication between the said portion of the housing and the second stage inlet space.

4. A two-stage, series-parallel pump comprising: a housing; first and second stage impeller casings mounted within the housing and laterally spaced from each other and from the housing side walls to provide first stage inlet spaces between the first stage casing and its proximate housing side wall and between the casings, and a second stage inlet space between the second stage casing and its proximate housing side wall; a water inlet to the housing adapted to supply all three of said inlet spaces; a large capacity first stage impeller and a smaller capacity second stage impeller mounted in the respective casings; dual casing inlets to the opposite sides of the first stage impeller communicating with said first stage inlet spaces, and a single casing inlet to

the second stage impeller communicating with said second stage inlet space; a discharge header; a first discharge passage from the first stage casing communicating with the header and with the second stage inlet space, and a second discharge passage from the second stage casing to the header; and valve means adapted for coupling the said casings and discharge passages to the header in series or in parallel.

5. A two-stage, series-parallel pump comprising: a housing; first and second stage impeller casings mounted within the housing and, with the housing, forming first and second stage inlet spaces; a water inlet to the housing adapted to supply both said spaces; a large capacity first stage impeller and a smaller capacity second stage impeller mounted in the respective casings and secured to a common shaft journalled in the said housing; a casing inlet to the first stage impeller communicating with said first stage inlet space, and a casing inlet to the second stage impeller communicating with said second stage inlet space; a discharge header; a first discharge passage from the first stage casing communicating with the header and with the second stage inlet space, and a second discharge passage from the second stage casing to the header; a manually operable valve movable to one position to direct the water flow in the first discharge

passage to the header only and to another position to direct such flow to the second stage inlet space only; and valve means responsive to movement of the said manually operable valve to its said position, respectively, to open and to close off communication between the housing and the second stage inlet space.

6. A two-stage, series-parallel pump comprising: a housing; first and second stage impeller casings mounted within the housing and, with the housing, forming first and second stage inlet spaces; a water inlet to the housing adapted to supply both said spaces; a large capacity first stage impeller and a smaller capacity second stage impeller mounted in the respective casings and secured to a common shaft; a casing inlet to the first stage impeller communicating with said first stage inlet space, and a casing inlet to the second stage impeller communicating with said second stage inlet space; a discharge header; a first discharge passage from the first stage casing communicating with the header and with the second stage inlet space, and a second discharge passage from the second stage casing to the header; and valve means adapted for coupling the said casings and discharge passages to the header in series or in parallel.

ALLAN G. SHEPPARD.
